No. 767,753.

PATENTED AUG. 16, 1904.

C. W. HARPER.
TELEPHONE TRANSMITTER.
APPLICATION FILED SEPT. 12, 1902.

NO MODEL.

UNITED STATES PATENT OFFICE.

CHARLES W. HARPER, OF MALDEN, MASSACHUSETTS.

TELEPHONE-TRANSMITTER.

SPECIFICATION forming part of Letters Patent No. 767,753, dated August 16, 1904.

Application filed September 12, 1902. Serial No. 123,060. (No model.)

To all whom it may concern:

Be it known that I, CHARLES W. HARPER, a citizen of the United States, and a resident of Malden, in the county of Middlesex and State 5 of Massachusetts, have invented new and useful Improvements in Telephone-Transmitters, of which the following is a specification.

Figure 1 is a side view of my improved transmitter, the cover of the casing being removed to expose the interior. Fig. 2 is a section on line 2 2 of Fig. 1. Fig. 3 is a detail of some of the parts of the transmitter shown in Figs. 1 and 2. Fig. 4 shows a complete telephone system embodying one form of my 15 invention applied to the person of an individual.

My invention relates to telephone-transmitters, and has for its object to improve the construction of the same to the end that better results may be secured in the transmission and reproduction of sound or speech than has been possible heretofore.

Particularly my invention has for its object to provide an improved telephone-transmitter especially adapted for use by individuals more or less deaf and to be carried upon the person of such individuals without inconvenience to them.

The novel features of my invention are 30 hereinafter fully set forth in the following description, and particularly pointed out and clearly defined in the claims at the close thereof.

Having reference to the drawings, T represents the transmitter, the diaphragm 1 of which is made, preferably, of aluminium and has fastened upon one face a disk 2, of carbon, which constitutes the movable electrode. The edge of diaphragm 1 is covered 35 by a band 3, of rubber or other cushioning and insulating material, and this edge is clamped between a seat 4, provided on a frame 5, and a clamping member 6. The clamping member 6 is exteriorly screw-threaded to engage threads upon the interior of frame 5, so that it may be caused to clamp the diaphragm 1 more or less firmly on its seat. The clamping member 6 is made with a cross-bar 61, in which is mounted a screw 7, locked in ad-

justed position by a set-screw 71. At its inner end screw 7 is reduced and engages an interiorly-screw-threaded socket provided on a holder 8, in which socket-screw 8 is locked by a set-screw 9. Holder 8 carries the fixed electrode 10 and also a ring 11, of cotton, felt, or other suitable material, within which is a body of carbon-granules 12. Upon cross-bar 61 is fastened a block 13, of insulating material, which carries a resilient contact member 14, whose end bears on electrode 2. The degree of pressure of contact member 14 on electrode 2 is regulated by a screw 15, and this contact member 14 serves not only as an electrical connection, but also to control and regulate the action of diaphragm 1 to some extent.

The frame 5 is made in the form of a ring, and its exterior is screw-threaded to engage screw-threads provided on the interior of a casing 16, of hard rubber or other suitable material, which is provided with a removable back 161, permitting access to the interior. Through this casing extends a sleeve 17, which at its inner end is connected with frame 5. This sleeve serves as a socket for a removable plug 18, fast to a switch-block 19 and connected by wire 181 with one pole of a battery B. Another sleeve 20 extends through casing 16 and is connected by wire 21 with member 14. This sleeve 20 is insulated from frame 5 by a sleeve 22. Sleeve 20 serves as a socket for a plug 23, fast on switch-block 19 and connected by wire 231 with the other pole of battery B through the receiver R.

Socket 17 and plug 18 are made larger than 85 socket 20 and plug 23, so as to make it impossible to connect the wrong pole of battery B with either socket 17 or 20. The plugs 18 and 23 are split longitudinally and sprung so as to frictionally engage the sockets when 90 forced into them.

The front wall 162 of casing 16 is provided with a centrally-arranged group of perforations 163, and it also is provided upon its interior face with an annular groove 164, which 95 latter I find greatly improves the acoustic properties of the chamber in front of the diaphragm 1. This chamber is also greatly im-

proved in this respect by making its periphery beveled, as at 25.

By my invention a very simple and effective telephone-transmitter is provided which can be worn upon the person without inconvenience and by which, owing to the peculiar sensitiveness thereof, a very much larger part of the effective sound conveyed is transmitted to the receiver.

10 It will be obvious that the problem presented in adapting a telephone-transmitter to the use to which I put it and in the manner in which I employ it is different from that presented by the ordinary speaking-telephone, 15 as for practical use it is desirable, in the first instance, that the speaker may be at any reasonable distance from the transmitter, at such a distance, in fact, as in ordinary conversation persons may naturally be placed, while 20 in the ordinary telephone-transmitter the speaker places his lips close to the transmitter.

It will be recognized by those skilled in the art that the ordinary transmitter employed in 25 such a manner as I have described and for such a purpose would be ineffective, while by my improved transmitter the sounds received are owing to its peculiar arrangement and adjustment transmitted in full volume to the 30 receiver and to the ear of the user.

My improved transmitter is designed to be 35 adjusted to suit the peculiar needs of the individual for whose use it is designed. The ears of deaf persons vary from a very slight defect to a deafness which notes only very great noises, and for this reason it is requisite and necessary that the instrument be 40 adjusted to the individual for reasons which will appear later in this specification. I have found that the loudness or volume of sound which the transmitter causes the receiver to produce is to a large degree proportionate to the pressure of the annular knife-edges of the 45 clamping members on the diaphragm. It is a fact, however, that while an increase of pressure on the diaphragm will cause an increase in the volume of sound produced at the 50 receiver, yet this increase is not accomplished without detracting slightly from distinctness of articulation. This, however, is not serious and in a measure corrects itself, since the ear of the user soon learns to translate without effort and automatically the sounds thus presented to the ear, although fuller and less 55 articulate than the sounds normally heard. I have, however, succeeded in minimizing this result of slightly-defective articulation by the use of the finger 14, by the regulation of which a clear articulation of the instrument 60 may be in a very large part restored without detracting in any measurable degree from the volume of sound gained by the use of pressure around the periphery of the diaphragm. Thus by means of the clamping member 6 and spring-finger 14 the instrument

may be adjusted to suit any ear and when properly adjusted will give a large volume of sound and very good articulation.

By providing the seat for the diaphragm on a metal frame which carries all the parts of the instrument those parts may be quickly set up and perfectly and permanently adjusted before the frame is put in the casing, which is a desirable feature. Also as the frame and clamping member are both preferably made 75 of the same material there is no unequal expansion between those parts to destroy the adjustment thereof.

By mounting the small carbon disk 2 on diaphragm 1 instead of providing a separate carbon diaphragm, as heretofore, the sensitivity of the instrument is increased to a marked degree, while the movements of the diaphragm cause finger 14 to rub on disk 2 and to thereby maintain a clean and perfect contact between 85 the two parts.

What I claim is—

1. In a transmitter in combination, a frame provided with an annular knife-edge; a clamping member adjustably mounted on said frame 90 and provided with an annular knife-edge of the same diameter as the knife-edge on the frame and directly opposed thereto; and a diaphragm clamped near its edge between the annular knife-edge on the frame and the annular knife-edge on the clamping member.

2. The above-described transmitter comprising a frame provided with an annular knife-edge; a clamping member adjustably mounted on said frame and provided with an annular knife-edge of the same diameter as the knife-edge on the frame and directly opposed thereto; a diaphragm clamped near its edge between the annular knife-edge on the frame and the annular knife-edge on the clamping member; an electrode controlled by the diaphragm; a fixed electrode; and an adjustable resilient finger acting on the diaphragm.

3. The above-described transmitter comprising a metal frame provided with an annular knife-edge; a metal clamping member adjustably mounted on said frame and provided with an annular knife-edge of the same diameter as the knife-edge on the frame, and directly opposed thereto; a metal diaphragm 115 clamped near its edge between the annular knife-edge on the frame and the annular knife-edge on the clamping member; insulation between the two knife-edges and the diaphragm; an electrode controlled by the diaphragm; a fixed electrode and an adjustable resilient finger resting against said diaphragm.

4. The above-described transmitter comprising an interiorly-threaded casing; an exteriorly and interiorly threaded ring screwed into the casing provided with an annular knife-edge diaphragm-seat; an exteriorly-threaded clamping-ring provided with an annular knife-edge of the same diameter as the first knife-edge and directly opposed thereto; a dia- 125

phragm clamped near its edge between the two knife-edges; an electrode controlled by the diaphragm, and a fixed electrode.

5. The improved transmitter above described, comprising an interiorly-threaded casing; an interiorly and exteriorly threaded ring screwed into said casing, said ring being made with an inwardly-projecting diaphragm-seat; an exteriorly-threaded clamping-ring screwed 10 into the first-mentioned ring; a diaphragm clamped near its edge between the diaphragm-seat and said clamping-ring; an electrode connected with the diaphragm, and an adjustable fixed electrode mounted centrally on the 15 clamping-ring.

6. The improved transmitter above described comprising an interiorly-threaded casing; an interiorly and exteriorly threaded ring screwed into said casing, said ring being made 20 with an inwardly-projecting diaphragm-seat; an exteriorly-threaded clamping-ring screwed into the first-mentioned ring; a diaphragm clamped near its edge between the diaphragm-seat and said clamping-ring; an electrode 25 mounted on the diaphragm; a resilient finger mounted on but insulated from the clamping-ring; said finger arranged to bear upon said electrode, and a fixed electrode mounted on the clamping-ring.

- 30 7. The improved transmitter above described comprising an interiorly-threaded casing made of non-conducting material, an interiorly and exteriorly threaded ring screwed into said casing said ring being made with an 35 inwardly-projecting diaphragm-seat; an exteriorly-threaded clamping-ring screwed into the first-mentioned ring, said clamping-ring being made with a cross-bar; a diaphragm clamped near its edge between the diaphragm-seat and said clamping-ring; an electrode 40 mounted on the diaphragm; a resilient finger mounted on but insulated from the clamping-ring, said finger being arranged to bear upon said electrode; means to regulate the pressure 45 of said finger on said electrode and a fixed electrode mounted on the cross-bar of the clamping-ring.

8. The improved transmitter above described comprising an interiorly-threaded casing 50 made of non-conducting material; an interiorly and exteriorly threaded ring screwed into said casing, said ring being made with an inwardly-projecting diaphragm-seat; an exteriorly-threaded clamping-ring screwed 55 into the first-mentioned ring, said clamping-ring being made with a cross-bar; a metal diaphragm clamped near its edge between the diaphragm-seat and said clamping-ring; a ring of insulating material between the border of 60 the diaphragm and the two rings; an electrode mounted on the diaphragm; a resilient finger mounted on but insulated from the clamping-ring, said finger being arranged to bear upon said electrode; means to regulate the pressure 65 of said finger on said electrode; a fixed elec-

trode mounted on the clamping-ring, and a pair of terminals one of which is connected with said finger and the other with one of said rings.

9. The improved transmitter above described, comprising an interiorly - threaded casing; an exteriorly and interiorly threaded ring screwed into said casing, said ring being made with an inwardly-projecting knife-edge diaphragm - seat; an exteriorly - threaded 70 clamping - ring screwed into the first - mentioned ring, said clamping - ring being made with a cross-bar and with an annular knife-edge opposed to the knife-edge diaphragm - seat on the outer ring; a diaphragm clamped near 75 its edge between the diaphragm - seat and the annular knife-edge on the clamping - ring; an electrode mounted on the diaphragm; a resilient finger mounted on but insulated from the clamping - ring; said finger being arranged to 80 bear upon said electrode; means to regulate the pressure of said finger on said electrode; a fixed electrode mounted on the cross - bar of the clamping - ring, and means to adjust the fixed 85 electrode on the cross - bar of the clamping - ring 90 toward and from the electrode on the diaphragm.

10. The improved transmitter above described comprising an interiorly - threaded casing; an exteriorly and interiorly threaded 95 ring screwed into said casing, said ring being made with an inwardly-projecting diaphragm - seat; an exteriorly - threaded clamping - ring screwed into the first - mentioned ring, said 100 clamping - ring being made with a cross - bar; a diaphragm clamped near its edge between the diaphragm - seat and the clamping - ring; an electrode mounted on the diaphragm; a resilient finger mounted on but insulated from the clamping - ring, said finger being arranged to 105 bear upon said electrode; means to regulate the pressure of said finger on said electrode; a screw mounted on said cross - bar with its axis normal to the plane of the diaphragm; a 110 holder detachably fixed to the end of said screw adjacent the diaphragm; and a fixed electrode supported by said holder.

11. The improved transmitter above described comprising an interiorly - threaded casing; an exteriorly and interiorly threaded 115 ring screwed into said casing; said ring being made with an inwardly-projecting diaphragm - seat; an exteriorly - threaded clamping - ring, said clamping - ring being made with a cross - bar a diaphragm clamped near its edge between the diaphragm - seat and the clamping - ring; an electrode mounted on the diaphragm; a resilient finger mounted on but insulated from the clamping - ring; said finger being arranged to bear upon said electrode; means to 120 regulate the pressure of said finger on said electrode; a screw mounted on said cross - bar with its axis normal to the plane of the diaphragm; means to lock said screw in adjusted 125 position; a holder detachably fixed to the end 130

of said screw between the cross-bar and the electrode on the diaphragm; and a fixed electrode supported by said holder.

12. The improved transmitter above described comprising an interiorly-threaded casing; an exteriorly and interiorly threaded metal ring screwed into said casing, said ring being made with an inwardly-projecting diaphragm-seat; an exteriorly-threaded metal 10 clamping-ring screwed into the first-mentioned ring, said clamping-ring being made with a cross-bar and with an annular knife-edge of the same diameter as the diaphragm-seat on the outer ring; a metal diaphragm 15 clamped near its edge between the diaphragm-seat and the annular knife-edge on the clamping-ring; a cushioning-ring of non-conducting material insulating the diaphragm from the two rings; an electrode mounted on the 20 diaphragm; a resilient finger mounted on but insulated from the clamping-ring; said finger being arranged to bear upon said electrode; means to regulate the pressure of said finger on said electrode, a screw mounted in said 25 cross-bar with its axis normal to the plane of the diaphragm; means to lock said screw in adjusted position; a holder detachably fixed to the end of said screw between the cross-bar and the electrode on the diaphragm; a 30 fixed electrode supported by said holder; a pair of terminals extending through the wall of said casing, one of said terminals being connected with the resilient finger and the other with one of said rings.

- 35 13. The improved transmitter above described comprising a closed interiorly-threaded casing of non-conducting material, made with an opening in its front wall and equipped

with means for attaching it to a person; an exteriorly and interiorly threaded metal ring 40 screwed into said casing, said ring being made with an inwardly-projecting reentrant knife-edge diaphragm-seat; an exteriorly-threaded metal clamping-ring screwed into the first-mentioned ring, said clamping-ring being 45 made with a cross-bar and with an annular knife-edge of the same diameter as the knife-edge on the outer ring; a metal diaphragm clamped near its edge between the two knife-edges; a cushioning-ring of non-conducting 50 material insulating the diaphragm from the two rings; an electrode mounted on the diaphragm; a resilient finger mounted on but insulated from the cross-bar of the clamping-ring, said finger being arranged to bear upon 55 said electrode; means to regulate the pressure of said finger on said electrode; a screw mounted in said cross-bar with its axis normal to the plane of the diaphragm; means to lock said screw in adjusted position; a holder detachably fixed to the end of said screw between the cross-bar and the electrode on the diaphragm; a fixed electrode supported by said 60 holder; a pair of terminals extending through the wall of said casing; one of said terminals being connected with the resilient finger and the other with one of said rings; and a disk of non-conducting material threaded on its periphery and screwed into said casing behind the two rings.

Signed by me at Boston, Massachusetts, this 8th day of September, 1902.

CHARLES W. HARPER.

Witnesses:
